UNITED STATES PATENT OFFICE.

FREDERICK J. GROSS, OF AUBURN, MAINE.

HEELED SHOE.

Application filed July 31, 1926. Serial No. 126,135.

This invention relates to the type of shoe known as a Goodyear welt shoe, and comprising an insole having a stitch-engaging lip, an upper, a welt, and an outsole, the 5 welt and upper being united by inseam stitches to the lip of the insole, and the outsole being united by outseam stitches to the welt.

A shoe of this type is popular and widely 10 used, because of its flexibility, and for other well known reasons.

It is customary to secure the lift heel of 15 a Goodyear welt shoe by nails driven through the heel and the heel portion of the 20 outsole on which the lift heel is seated. The nails are objectionable because they are liable to work through the upper surface of the heel portion of the insole, said surface constituting what I call the wearer's 25 heel seat, and injure the wearer's stocking and heel. It is the common practice to employ a large number of heel-attaching 30 nails, each nail being liable to become a source of objection.

25 The invention is embodied in a heeled Goodyear welt shoe, in which the wearer's heel seat is secured in its operative position conjointly by some of the inseam stitches, engaged with a portion of the welt, and by 30 some of the outseam stitches engaged with a lift heel, the heel portion of the outsole, and a portion of the welt, the object being to securely confine the wearer's heel seat in a smooth comfortable position, and 35 to prevent interruption of said heel seat and discomfort to the wearer by the fasteners employed to secure the lift heel, said fasteners being located wholly outside the wearer's heel seat and constituting the only 40 means for attaching the lift heel.

Of the accompanying drawings forming a part of this specification,—

Figure 1 is a side view of a shoe embodying the invention.

45 Figure 2 is a bottom view of the same.

Figure 3 is a section on line 3—3 of Figure 2.

Figure 4 is a view similar to a portion of Figure 3, showing the heel provided with a 50 supplemental lift.

The same reference characters indicate the same parts in all of the figures.

The insole 12 of a shoe characterized as 55 hereinafter described, is provided with a continuous outwardly turned lip 13. The lower marginal edge of the upper 14 is seat-

ed on the lip. A continuous welt 15 is seated on and projects outwardly from the upper, including the heel or counter portion thereof, and is united to the upper and to the 60 lip 13, by a continuous series of inseam stitches 16 formed by a Goodyear welt-sewing machine, while the upper, the insole, and the welt are on a last. The outsole includes a fore portion 17, and a heel portion 17^a, 65 whose margin is flush with the outer margin of the welt. The outsole is seated on the welt, the lower edge portion of the upper, the lip 13, and any suitable filler 18, covering the lower surface of the insole within 70 the lip. The filler is preferably a layer of leather or leather-board corresponding in thickness to the width of the lip 13. A lift heel 19, which may be composed of any suitable number of lifts, is seated on the heel 75 portion 17^a of the outsole.

The welt is united to the outsole and heel by a continuous series of outseam stitches 20 formed by an outsole stitcher, and passing through the marginal portion of the outsole 80 and through the marginal portion of the heel 19, excepting the breast thereof, and through the marginal portion of the welt. Said stitches are made by an outsole stitcher 85 organized to form outseam stitches of different lengths, so that relatively short stitches 20 are formed in the fore part of the outsole, and longer stitches 20^a in the heel portion of the outsole and in the heel 19.

The described shoe is characterized by the 90 fact that a portion of the welt and some of the inseam stitches attaching the welt to the insole, are extended around the heel portion of the upper, while some of the outseam stitches attaching the outsole to the welt, are 95 extended around the heel portions of the outsole and welt and engaged with the lift heel. The result is that the wearer's heel seat, formed by the heel portion of the insole, is securely confined in a smooth, comfortable position by the conjoint action of some of the inseam stitches and heel lift-attaching outseam stitches, the latter being located entirely outside the wearer's heel seat and constituting the only fasteners of 100 the lift heel, so that there can be no penetration of the wearer's heel seat by lift heel fasteners.

The heel 19 may be provided, as shown by Figure 4, with a supplemental heel lift 19^a, 110 which may be of rubber or any other suitable material. This lift covers the outer ends

of the longer out-seam stitches 20^a, and is secured to the body portion of the heel 19, and to the heel portion of the outsole by supplemental fasteners 22, which may be 5 wooden pegs and are located wholly outside the heel or counter portion of the upper, and in close proximity to the stitches 20^a, so that they are outside the wearer's heel seat under the wearer's heel. A shank piece 23, 10 preferably of wood, may be interposed between the filler 18 and the shank portion of the outsole.

It will be seen that the described heeled shoe is of entirely non-metallic construction.

I claim:

A Goodyear welt shoe including an insole, an upper, a welt extending completely around the shoe, inseam stitches uniting the 20 insole and upper to the welt, an outsole, out-seam stitches uniting the welt to the outsole,

and a lift-heel seated on the heel portion of the outsole, a portion of the welt and some of the inseam stitches attaching the welt and upper to the insole being extended around 25 the heel portion of the upper, while some of the outseam stitches attaching the outsole to the welt are extended around the heel portions of the outsole and welt and engaged with the lift-heel, the arrangement being 30 such that the heel seat of the shoe is marginally confined by the conjoint action of some of the inseam stitches, the outseam stitches connecting the welt and lift-heel being located entirely outside the heel seat 35 of the shoe and the lift-heel being secured entirely by said outseam stitches, so that there is no penetration of the heel seat of the shoe by lift-heel fasteners.

In testimony whereof I have affixed my 40 signature.

FREDERICK J. GROSS.
